SULFINAMIDES AS NEUTRALIZERS IN PERMANENT-WAVING OF THE HAIR

Jerome Luloff, East Paterson, and Yunn-Hui Chiang, New Milford, N.J., assignors to Shulton, Inc., Clifton, N.J., a corporation of New Jersey
No Drawing. Filed July 29, 1964, Ser. No. 386,058
6 Claims. (Cl. 167—87.1)

This invention relates to compositions and processes useful in the treatment of hair. More particularly it relates to compounds which are useful as neutralizers for the cold permanent setting of hair and processes for treating hair with such neutralizing compounds.

The waving of hair is accomplished by altering the configuration of the hair while it is maintained in a curled position. In "water waving" hair, a wet strand is wound in circular fashion on some sort of mandrel and allowed to dry. The disadvantage of this method is that the hair remains curled only in the absence of moisture and so is commonly called a "temporary set." In contrast permanent waving produces a "permanent set," presumably by altering some of the chemical forces in the hair that are stable to water at temperatures normally encountered by the human body.

Permanent waving basically involves a two-step process. In the first step, water-stable chemical forces are interrupted so that the hair may be set to the desired shape. This is accomplished through the use of a "waving lotion." The material which is widely used today as the active ingredient in waving lotions is thioglycolic acid, generally in the form of its salts. After the hair has been softened with waving lotion and formed into the desired configuration, it is necessary to reverse the action of the waving lotion. This reversal is accomplished by a second fluid which is commonly called a "neutralizer." The commonly used neutralizers are chemical oxidizing agents. Those in use today as the oxidizing ingredient in neutralizers are hydrogen peroxide and alkaline bromate salts.

The aforementioned neutralizers apparently affect not only the desired chemical functional groups in the hair, but since they are non-specific oxidizers, they apparently also affect other chemical moieties in the hair. While these side-effects have not been serious enough to make these substances wholly unacceptable for use as hair waving neutralizers, it has been found that they tend to bleach the hair, oxidize cystine to cysteic acid, damage pre-

2

viously bleached or dyed hair, split or break the hair filaments, and increase the likelihood of hair being damaged by exposure to sunlight.

This invention provides certain novel neutralizer compositions containing sulfinamides, some of which are novel, for use in permanent waving of hair. Especially useful in the practice of this invention are those sulfinamides having the formula:

wherein R₁ and R₂, which can be the same or different, and are hydrogen, lower alkyl, lower aminoalkyl, aryl, or, when taken together with the nitrogen atom to which they are attached, a mononuclear heterocyclic radical such as pyrrolidinyl, piperidinyl, piperazinyl, or morpholinyl which can be substituted with lower alkyl groups; R₃ is lower alkyl; lower alkylene; aryl; carbamoyl; carbamoyl alkylene, such as carbamoyl methylene, carbamoyl ethylene, or carbamoyl propylene; carboxyalkylene, such as carboxymethylene, carboxyethylene, or carboxypropylene; carboalkoxy, such as carbomethoxy, carboethoxy, or carbopropoxy; carboalkoxyalkylene, such as carbomethoxypropylene or carbopropoxymethylene; carboxy; or N-substituted carbamoyl wherein the substituent is lower alkyl, aryl, or carbamoyl groups in which the nitrogen is part of a heterocyclic ring which may be mono- or polynuclear, such as pyrrolidine, piperidine, piperazine, morpholine, quinoline or isoquinoline rings or such rings substituted with lower alkyl groups; and R₄ is hydrogen or lower alkyl. R₃ and R₄ can be the same or different. These substances are used in an amount effective to neutralize the action of thioglycolic acid or other such reducing materials contained in the permanent-waving lotion.

The sulfinamides used in the neutralizers of this invention may be applied to the hair in the form of aqueous solutions or in the form of emulsions comprising water and/or hydrophobic materials, such as glyceride oils. Exemplary of sulfinamides which have been found useful in the practice of this invention are shown in the following table where the generic formula of the sulfinamides is taken for convenience as

A preferred water-soluble sulfinamide for the practice of this invention is (4-morpholinosulfinyl) acetomorpholide:

The sulfinamides of this invention are conveniently applied to the shaped hair in aqueous solutions or emulsions which may contain other ingredients commonly used in commercial neutralizing preparations, such as glyceride or other oils, emulsifiers, hair conditioners, lubricants, perfumes, and preservatives. The neutralizer compositions can be provided ready for use or as concentrates which are diluted before use.

The sulfinamides of this invention may be present in solution in amounts up to the saturation point of the particular sulfinamide. Where emulsions are contemplated, amounts beyond saturation point of the sulfinamide can be incorporated. In general, it has been found that very low concentrations require a long period of time for the neutralizing action to be complete. On the other hand, the use of excessive amounts of sulfinamides in the neutralizer serves no useful purpose and merely increases the cost of the product.

Generally, it has been found that amounts of sulfinamide in the range of from about 0.04 mole to the saturation point of the sulfinamide in 1000 g. of aqueous solutions are satisfactory in the practice of this invention. The preferred range of concentrations is from about 0.2 to about 1.0 mole of the sulfinamide per thousand grams of total solution. Amounts of (4-morpholinosulfinyl) acetomorpholide on the order of 0.5 mole per 1000 g. of solution have been found to give excellent results as a neutralizer.

In performing the process of this invention, any of the waving lotions known in the art may be used. In addition to the thioglycolic acid and salts thereof previously mentioned, substances such as, for example, thioglycerol, beta-aminoethyl mercaptan, mercaptoethanol, mercaptobutane sulfonic acid, thioglycolamide, thiolactic acid, sulfites and bisulfides can be used.

Shaping of the hair to the desired configurations can be achieved by conventional methods. Curlers of either the spiral rod or croquinole type may be used. If other styles are desired, clamps of various types or bobby pins may be employed. If desired, the curling devices can be used in conjunction with end papers.

The sulfinamides of this invention can conveniently be prepared by a number of reaction routes. One method for preparing these substances is to react a mercaptan with chlorine followed by hydration to form the sulfinyl chloride and then to react this with an amino- or imino-

nitrogen-containing substance to obtain the desired sulfinamide. Another method is to react a dicarboxylic disulfide with chlorine and subsequently with amino- or imino-nitrogen-containing substance. A disulfide can also be chlorinated and hydrated to form the sulfinyl chloride derivative. The first three examples appearing below will illustrate a method for the preparation of a sulfinamide, and those skilled in the art will be able readily to apprehend still other routes for preparing sulfinamides.

In preparing the required intermediate sulfinyl chlorides, it is best to use a 3:1 molar ratio of chlorine to disulfide, except in the case of dithiodiglycolic acid where a 2:1 ratio is preferable. Higher ratios of chlorine can be used, but amounts of chlorine near the theoretical are generally found to produce the best results. Reaction between the chlorine and disulfide is usually effected in a lower alkanic acid, e.g., acetic or propionic acid using a reaction solvent such as methylene chloride. A temperature range of from about -20 to -70° C. is useful, although temperatures somewhat above or below this range may be employed without adverse effects. In the foregoing temperature range the reaction is generally completed during a period of from about one-half to about three hours. For efficiency, it is best to agitate the mixture during the reaction period, although this is not essential.

The product may be isolated by any convenient procedure. In one method the mixture is first allowed to come to room temperature, i.e. about 25° C., so as to permit the escape of hydrogen chloride. It is preferred, although not essential, to remove as much as possible of the hydrogen chloride from the reaction mixture. This may be accomplished by maintaining the mixture at a temperature from about 35° C. to about 60° C. for a brief period of time, e.g. one to two hours. The reaction mixture is then stripped at subatmospheric pressure at a temperature of from about 50° C. to about 60° C. to leave the desired acid chloride as a residue. The product may be recovered by distillation, preferably at low pressure.

The resulting sulfinyl chloride together with the selected amine or imine is taken up in a reaction-inert organic solvent, such as a hydrocarbon or halogenated hydrocarbon, and particularly lower saturated or unsaturated hydrocarbon or halogenated hydrocarbons such as hexane, benzene, methylene chloride, ethylene chloride, or bromobenzene, and maintained at a low temperature for a period of from about 15 minutes to 3 hours. The preferred temperature range is from about -20° to about 5° C., although temperatures somewhat above or below this range may be employed.

It is essential that this reaction be run in the absence of air and preferably in a nitrogen atmosphere.

The product is most simply recovered by filtering off the amine hydrochloride and subsequently evaporating the filtrate to dryness under reduced pressure. The product can be purified by distillation or recrystallization.

Example I

A total of 91 grams (0.5 mole) of dithiodiglycolic acid and 60.1 grams (1.0 mole) of glacial acetic acid are mixed in a 500 ml. flask fitted with a stirring device, a gas inlet tube extending into the liquid, a gas outlet tube, and a thermometer. The mixture is cooled to -70° C. in a solid carbon dioxide-acetone bath and 115 grams (1.5 mole) of chlorine are introduced during a one-hour period. After the introduction of chlorine the reaction mixture is stirred for an additional half-hour, whereupon the cooling bath is removed and the mixture allowed to come to room temperature. Finally, the solution is warmed to 40° C. to permit any remaining hydrogen chloride to escape.

This reaction mixture is distilled at atmospheric pressure to remove all material boiling at temperatures below 54° C. The remaining mixture is then distilled under reduced pressure to remove acetyl chloride.

The impure sulfinyl chloride so obtained is dissolved in methylene chloride and slowly added to a methylene chloride solution containing 174 grams (2.0 moles) of morpholine while cooling with an ice bath and stirring. After the addition of the sulfinyl chloride is complete, stirring is continued for an additional one-half hour. The mixture so obtained is filtered and the filtrate concentrated. The solids obtained by concentration of the filtrate are combined with the original precipitate and crystallized to obtain white crystals melting at $183-185^{\circ}$ C. This material is then recrystallized from ethanol to obtain a crystalline material with a melting point of $188-189^{\circ}$ C. The elemental analysis shows:

	Percent C	Percent H	Percent N	Percent S
Calc.	45.78	6.91	10.68	12.23
Obs.	46.03	6.51	10.46	12.06

Example II

A total of 91 grams (0.5 mole) of dithiodiglycolic acid and 250 ml. of methylene chloride are mixed in a 1000 ml. flask fitted with a stirring device, a gas inlet tube extending into the liquid, a gas outlet tube, and a thermometer. The mixture is cooled to -20° C. in a solid carbon dioxide-acetone bath and 71 grams (1 mole) of chlorine are introduced during a one-hour period. After the introduction of chlorine the reaction mixture is stirred for an additional half-hour, whereupon the cooling bath is removed and the mixture allowed to come to room temperature. Finally, the solution is warmed to 40° C. to permit any remaining hydrogen chloride to escape.

This reaction mixture is distilled at atmospheric pressure to remove all material boiling at temperatures below 54° C.

The impure sulfinyl chloride so obtained is dissolved in methylene chloride and slowly added to a methylene chloride solution containing 348 grams (4.0 moles) of morpholine while cooling with a solid carbon dioxide-acetone bath and stirring. After the addition of the sulfinyl chloride is complete, stirring is continued for an additional one-half hour. The mixture so obtained is filtered and the filtrate is concentrated. The solids obtained by concentration of the filtrate are combined with the original precipitate and crystallized to obtain white crystals melting at $183-185^{\circ}$ C. This material is then recrystallized from ethanol to obtain a crystalline

material with a melting point of $188-189^{\circ}$ C. The elemental analysis shows:

5		Percent C	Percent H	Percent N	Percent S
	Calc.	45.78	6.91	10.68	12.23
	Obs.	45.68	7.07	10.55	12.45

Example III

Thirty grams (0.5 mole) of glacial acetic acid, 30.5 grams (0.25 mole) of ethyl disulfide and 200 ml. of dry methylene chloride are introduced into a 500 ml. four-necked flask equipped with an agitator, a solid carbon dioxide cooling trap, a gas inlet tube, and a thermometer, and the reaction vessel is immersed in a solid carbon dioxide-acetone cooling bath to maintain the contents of the flask at 0° to -10° C. Then 54 grams (0.75 mole) of chlorine are passed into the mixture during a 45-minute period. After 30 minutes of chlorine addition, the temperature is reduced to -10° to -15° C. to minimize evolution of hydrogen chloride and the attendant loss of chlorine.

25 After the addition of chlorine has been completed the cooling bath is removed, and the mixture is permitted to warm to room temperature with continued agitation. Vigorous evolution of hydrogen chloride occurs. The mixture is subsequently brought to 35° C. to drive off the 30 remaining hydrogen chloride. The resulting reaction mixture is distilled at atmospheric pressure until it reaches 100° C. and most of the by-product acetyl chloride is removed. The residue is rapidly cooled at temperature of 20° C. or less and transferred to a smaller flask for distillation under reduced pressure.

35 The ethanesulfinyl chloride formed is recovered by collecting the fraction boiling at $48-52^{\circ}$ C. at 18 mm. Hg. The yield of this sulfinyl chloride is 38.4 grams, or 68.4% of theory.

40 Twenty-two grams (0.3 mole) of diethylamine and 150 ml. of dry methylene chloride are placed in a 500 ml. four-necked flask equipped with agitator, gas cooling condenser, gas inlet tube, thermometer, and pressure-balanced dropping funnel. The gas cooling condenser is 45 filled with a solid carbon dioxide-acetone mixture and nitrogen was passed through the system. The flask is cooled with a solid carbon dioxide-acetone bath to maintain an internal temperature of 0° to -10° C.

A solution of 17 grams (0.15 mole) of ethane sulfinyl 50 chloride in 150 ml. of dry methylene chloride is added over a one-hour period. After the addition is complete, the cooling bath is removed and the mixture is allowed to warm for one-half hour with agitation. A white precipitate in the amount of 12.82 grams with a melting point of $230-231^{\circ}$ C. is obtained, removed by filtration and identified as diethylamine hydrochloride.

The filtrate is distilled and the diethylethanesulfinamide is recovered as the fraction boiling at 55° C. at a pressure of 1.30 mm. Hg.

Example IV

The (4-morpholinosulfinyl) acetomorpholide obtained in Example I is used to curl hair according to the technique of Kirby, "Waving Efficiency of Cold Permanent Wave Lotion," Drug and Cosmetic Industry, volume 80, 65 Number 3, page 314 et seq. (March 1957). In this technique samples of hair are wound through a set of pegs and then successively exposed to a waving lotion and a neutralizer. The air is removed from the pegs after treatment and a measurement of the length is made 70 and compared with the original measurement. The length after treatment with effective cold waving compounds is less due to the shortening of the hair strands because of the waves set up therein, and the ratio of lengths before and after treatment is used to calculate the efficiency of the material under test.

In tests conducted on thioglycolate-treated hair neutralized with the above-prepared sulfinamide at a concentration of 0.04 mole per 1000 g. of aqueous solution, the curl efficiency is as shown in Table II.

TABLE II

Time of exposure to neutralizer (min.):	Efficiency, percent
5	12.5
10	32.8
20	34.9

The efficiency value for twenty minutes of treatment compares favorably with values obtained using potassium bromate neutralizers in the same test. However potassium bromate and other known neutralizers do not have the advantages of the neutralizer compositions of this invention, as indicated in the following example.

Example V

In a further test, permanents are given to women using the sulfinamide neutralizers of Example I in conjunction with conventional thioglycolate waving lotions. Solutions of the above-prepared sulfinamide at a concentration of 0.5 mole/1000 g. total solution are used to neutralize the previously treated hair for a period of thirty minutes. Compared to standard bromate or peroxide neutralizer results, permanents with the sulfinamide neutralizer of this invention give smoother, more manageable waves without kinkiness or "frizzing." Comparable results are obtained with the materials shown in Table I.

Although a certain particular embodiment of the invention is herein disclosed for purposes of explanation, various modifications thereof, after study of this specification will be apparent to those skilled in the art to which the invention pertains. Reference should accordingly be had to the appended claims in determining the scope of the invention.

What is claimed and desired to be secured by Letters Patent is:

1. (4-morpholinosulfinyl) acetomorpholide.
2. Isopropyl sulfinamide.

3. A permanent-waving neutralizer aqueous composition containing 0.2 to 1.0 mole per thousand grams of total solution of a sulfinamide selected from compounds having the formula:

wherein R_1 and R_2 are selected from the group consisting of hydrogen, methyl, ethyl, and when taken together with the nitrogen atom to which they are attached, morpholinyl and R_3 is selected from the group consisting of hydrogen, methyl, ethyl, propyl, isopropyl, and carbamoyl in which the nitrogen atom is part of a morpholine ring.

15 4. A permanent-waving neutralizer aqueous composition containing 0.2 to 1.0 mole per thousand grams of total solution of (4-morpholinosulfinyl) acetomorpholide.

5 In the process of permanent-waving hair which comprises treating the hair with a waving lotion, shaping 20 the hair to the desired configuration, and treating the hair with a neutralizer, the improvement which comprises using as the neutralizer an aqueous composition containing a sulfinamide selected from compounds having the formula:

wherein R_1 and R_2 are selected from the group consisting of hydrogen, methyl, ethyl, and when taken together with the nitrogen atom to which they are attached, morpholinyl and R_3 is selected from the group consisting of hydrogen, methyl, ethyl, propyl, isopropyl, and carbamoyl in which the nitrogen atom is part of a morpholine ring.

30 35 6. The process of claim 5 in which the sulfinamide is (4-morpholinosulfinyl) acetomorpholide.

No references cited.
